UNITED STATES PATENT OFFICE.

OSIAS O. KRUH, OF SCHENECTADY, NEW YORK, ASSIGNOR TO GENERAL ELECTRIC COMPANY, A CORPORATION OF NEW YORK.

VAPOR ELECTRIC APPARATUS.

1,086,185.

Specification of Letters Patent. Patented Feb. 3, 1914.

Application filed February 20, 1904. Serial No. 194,520.

To all whom it may concern:

Be it known that I, OSIAS OTTO KRUH, a subject of the Emperor of Austria-Hungary, residing at Schenectady, in the county of 5 Schenectady and State of New York, have invented certain new and useful Improvements in Vapor Electric Apparatus, of which the following is a specification.

My invention relates to vapor electric apparatus and more especially to the use of 10 such apparatus for rectifying alternating current.

Among the objects of my invention is the production of an organization which is not 15 subject to arcing between the anodes.

The novel features characteristic of my invention are set forth with particularity in the appended claims.

As an illustration of my invention I have 20 set forth in detail in the following specification certain embodiments of my invention and have represented them pictorially in the accompanying drawings, in which—

Figure 1 represents a rectifier embodying 25 my invention; Fig. 2 is a modified form of rectifier; Fig. 3 is a diagram of circuits forming a part of the rectifier system; and Fig. 4 is a diagram of a novel arrangement of rectifier system.

30 The arcing between the anodes of a rectifier, which it is one of the purposes of my invention to avoid, may be due to a number of causes. Thus globules of mercury may fall back through the usual arc stream in 35 the rectifier and, by being then suddenly vaporized, cause an increase in the vapor pressure and a corresponding sudden increase in the voltage drop in the rectifier. The sudden change thus imposed on the 40 supply system may cause a momentarily existing high voltage which may be sufficient to cause a flash or arc between the anodes. Probably, however, the most prolific source of arcing between the 45 anodes is due to globules of condensed mercury coming in contact with the anodes. Thus, for example, drops of mercury from the condensing chamber may fall against the anode or, in falling into the cathode, 50 may cause other drops to splash up against the anode. The sudden disturbance thus produced on the anode surface may cause a negative ionization to take place at the anode and thus provide the basis for a

flash or discharge between the coöperating 55 anodes.

I have found that the trouble mentioned may be completely overcome by so arranging the anodes that they are entirely out of the path traversed by mercury globules and 60 by so arranging the condensing chamber that the return flow of mercury does not pass through the normal rectifier arc.

Numerous forms of rectifiers may be made embodying my invention. One form is indicated in Fig. 1. In this figure a highly exhausted envelop of glass or other suitable material is indicated at 1. At the lower portion of this envelop pockets are formed containing bodies of mercury indicated at 2 and 3. The mercury body 2 constitutes the cathode or negative electrode while the body of mercury 3 adjacent thereto serves as an auxiliary or starting anode. Branching off from the main envelop 1, and slightly inclined from the horizontal, are two oppositely located tubes 4 and 5 opening into the envelop 1. In these tubes are located respectively suitable anodes 6 and 7 of artificial graphite or other suitable material. 80 All of the electrodes mentioned are provided in the usual manner with leading-in conductors for conveying current between the electrodes and the external circuits of the rectifier.

85 The main body of the rectifier, above the cathode 2, communicates with the vertical condensing chamber 8 and is slightly inclined so that when drops of mercury fall from the condensing chamber they roll 90 slowly into the cathode 2. In order to decrease still further the velocity of the returning mercury, the inclined portion of the envelop may be corrugated or provided with ridges as shown, for example, at 9. 95

In connecting up the rectifier for use a system of circuits may be employed such as shown in Fig. 3. In this figure the alternating-current supply mains are represented at 10 and 11. These are connected respectively to the anodes 6 and 7. The starting anode 3 is connected through a switch 12 and a current limiting resistance 13 to either one of these mains as, for example, to the main 10. The cathode 2 is connected through the consumption circuit of the rectifier to the junction 14 between two inductance coils 15 and 16 in series with each other between

the mains 10 and 11. In the consumption circuit current-consuming devices of any desired character may be employed as, for example, a storage battery 17.

- 5 In starting the rectifier the receptacle is tilted or shaken so that, by means of the momentary flow of mercury between the electrodes 2 and 3, an auxiliary or starting arc is produced which serves to initiate the 10 main arcs between the cathode 2 and the main anodes 6 and 7. A resistance in the consumption circuit may be used for starting and afterward replaced by translating devices. The method of starting the rectifier and its mode of operation are well understood and require no further description.

When the rectifier has been started mercury condenses in the chamber 8 and drops back from time to time. By reason of the 20 location of the condensing chamber, the mercury in falling cannot drop through the arc between the cathode and the anodes 6 and 7. By thus controlling the falling of the mercury no disturbing effect upon the vapor 25 pressure appears and one of the contributory causes of trouble in the operation of the rectifier is removed.

The anodes 6 and 7, being located in 30 chambers extending off from the main rectifying chamber, are entirely out of the path of mercury returning from the condensing chamber 8. They are also out of the path of any globules which might from any cause be splashed up from the cathode 2. Being 35 so protected, no negative ionization can take place, whereby another prolific cause of arcing between the anodes is removed.

Although practically all of the mercury 40 is condensed in the chamber 8 it may happen from time to time that small globules of mercury will form in the tubes 4 and 5. The condensation in these tubes, however, is very small because of the presence of the heated anodes therein. In order, however, 45 to guard against the very slight possibility of trouble from this source I may surround the anodes by protecting shields as represented at 19 and 20 in Fig. 2. In this figure the rectifier shown is practically the same as 50 that in Fig. 1 except for the presence of the shields 19 and 20 and for the further modification in which the starting anode 21, instead of being located as in Fig. 1, is formed in the main tube just below the condensing chamber 22. The pocket containing 55 the mercury electrode 21, therefore, serves the double purpose of an electrode container and as an intercepting means for preventing the return flow of mercury from reaching 60 the cathode 23 by sudden movement such as would cause disturbance of the surface of the cathode.

Instead of using the system of connections 65 for the rectifier as shown in Fig. 3 I have found that good results may be obtained by

the arrangement shown in Fig. 4. In this figure a winding 24, which may be the secondary of a transformer or any other winding producing alternating current, constitutes the source of current. The terminals to the winding are connected respectively to the anodes of the rectifier as, for example, the anodes 25 and 26 of the rectifier shown in Fig. 2. The cathode 23 is connected through the consumption circuit to the middle or other intermediate point 27 in the winding 24. The starting electrode 21 is connected through a switch 28 and current-limiting resistance 29 to one of the leads of the winding 24.

In order to provide for the existence of overlapping arcs between the respective anodes and the cathode, as is necessary to the operation of a rectifier of this character, I connect inductance coils 30 and 31 in the 75 respective leads extending to the anodes 25 and 26. The energy storing and re-storing action of the inductance coils has the effect of maintaining the arc or discharge from one anode while the other anode is not in a condition to maintain its arc or, in other words, when it is passing over its dead point, so to speak.

It will be evident to one skilled in the art 90 that numerous variations may be made in the embodiment of my invention without departing from the spirit thereof for which reason I do not wish to be limited to the exact details shown and described.

What I claim as new and desire to secure 100 by Letters Patent of the United States, is,

1. The combination of a source of alternating current, mains extending therefrom, anodes connected respectively to said mains, inductance coils in series respectively in said 105 mains, and a cathode connected to a circuit extending from a point of intermediate potential in said source.

2. The combination of a winding, mains extending therefrom, anodes connected respectively to said mains, energy storing and restoring devices in circuit respectively with 110 said mains, and a cathode connected to an intermediate point in said winding.

3. The method of operating vapor electric apparatus having a vaporizable cathode and a plurality of anodes, which consists in returning the products of condensation to the cathode so that they neither traverse the main arc in the apparatus nor come in contact with either of the anodes.

4. In a vapor rectifier, the combination of an exhausted receptacle, a liquid negative electrode therein, a plurality of anodes therein, an insulating chamber surrounding each anode, each chamber being provided with an opening in a plane substantially at right angles to the plane of the surface of the negative electrode.

5. The combination of an exhausted re- 130

- ceptacle, a cathode, a plurality of solid electrodes adapted to operate as anodes, and an insulating shield for one at least of said anodes.
- 5 6. The combination of an exhausted envelop or receptacle, a vaporizable electrode or cathode, a plurality of solid electrodes adapted to operate as anodes, and means for shielding one at least of said anodes to prevent arcing between them.
- 10 7. The combination of an exhausted envelop or receptacle, an electrode adapted to operate as a cathode, a plurality of electrodes adapted to operate as anodes, and a glass shield for each of said anodes.
- 15 8. In a vapor electric apparatus, the combination of an exhausted receptacle, a liquid negative electrode therein, a plurality of
- anodes therein, and a shield for each anode for preventing arcing between the anodes. 20
9. In a system of electrical distribution, a source of single-phase alternating current, a direct current work circuit supplied therefrom, an interposed vapor converter having a suitable negative electrode and a plurality 25 of positive electrodes, and an inductance introduced into each of the leads of the positive electrodes to maintain the converter in operative condition.

In witness whereof, I have hereunto set 30
my hand this 19th day of February, 1904.

OSIAS O. KRUH.
